UNITED STATES PATENT OFFICE.

HENRY J. HUGHES, OF NEW YORK, N. Y.

NET.

No. 827,868.

Specification of Letters Patent.

Patented Aug. 7, 1906.

Application filed October 11, 1905. Serial No. 282,263.

To all whom it may concern:

Be it known that I, HENRY J. HUGHES, a citizen of the United States, and a resident of the city of New York, borough of Manhattan, in the county and State of New York, have invented a new and Improved Net, of which the following is a full, clear, and exact description.

The invention relates to lawn-tennis, ping-pong, and like games in which use is made of a stretched net.

The object of the invention is to provide a new and improved net arranged to clearly and accurately indicate the side lines of the lawn-tennis court to aid the players in properly serving the ball and to readily determine whether a ball was passed over the net within the proper boundaries.

The invention consists of novel features and parts and combinations of the same, which will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement as applied to a double lawn-tennis court. Fig. 2 is an enlarged face view of the same, and Fig. 3 is a transverse section of the same on the line 3 3 of Fig. 2.

The net A, stretched across the tennis-court B, is secured at its ends in the usual manner to the posts C, preferably located outside the side lines B' B² of the tennis-court B, which latter is shown as a double court in Fig. 1. On the net A are arranged vertically-disposed outer sighting-guides D D' and D D' and the middle sighting-guide D², of which the sighting-guides D D' are located near the ends of the net A and are in transverse alinement with the corresponding side lines B' B² of the tennis-court B and the said middle sighting-guide D² is arranged in transverse alinement with the middle or dividing line B³ of the tennis-court.

Each of the sighting-guides D, D', and D² is preferably made of a strip of canvas or similar material fastened in any suitable manner to the net A, the strip of canvas being in contrast to the net A, so as to readily distinguish the sighting-guide from the net. If desired, the lower end of each strip may be connected with the ground by a suitable an-

choring device E, as plainly indicated in Fig. 2, to assist in holding the net properly stretched across the tennis-court B. If desired, the canvas strips may be detachably connected with the net A, so as to allow of placing the strips in proper position relative to the lines B', B², and B³ of the tennis-court when setting up the net.

By the arrangement described it will be seen that the sighting-guides D, D', and D² are arranged in vertical planes containing the corresponding side lines B', B², and B³, so as to aid the player in properly serving the ball and to allow of readily determining whether a ball was passed over the net within the proper boundaries.

In Fig. 1 a double court is shown, and consequently two end sighting-guides D D' are employed; but for a single court the sighting-guides D' are omitted.

The device is very simple and durable in construction, is not liable to get out of order, and the sighting-guides assist in strengthening the net A, besides having the useful functions above mentioned.

Having thus described my invention, I claim as new and desire to secure by Letters Patent—

1. A net for lawn-tennis and similar games, provided with sighting-guides arranged vertically on the net and in alinement with the side boundary-lines of the tennis-court.

2. A net for lawn-tennis and similar games, provided near each end with a vertically-disposed sighting-guide in alinement with the side boundary-line of the tennis-court.

3. A net for lawn-tennis and similar games, provided at each end with a sighting-guide in contrast to the body of the net and disposed in a vertical plane sustaining the side boundary-line of the tennis-court.

4. A net for lawn-tennis and similar games, provided, near each end, with spaced sighting-strips disposed vertically and in alinement with the side boundary-lines of a double tennis-court.

5. A net for lawn-tennis and similar games, provided, near each end, with spaced sighting-strips disposed vertically and in alinement with the side boundary-lines of a double tennis-court, and a vertical sighting-strip at the middle of the net and in alinement with the central dividing-line of a double tennis-court.

6. A net for lawn-tennis and similar games,

provided at each end with a sighting-guide in contrast to the body of the net and disposed in a vertical plane containing the side boundary-line of the tennis-court, and an
5 choring means for engaging the ground and connected with the lower end of the said sighting-guide.

In testimony whereof I have signed my name to this specification in the presence of two subscribing witnesses.

HENRY J. HUGHES.
